(57) **CLAIM**

The ornamental design for a keyboard with cover, as shown and described.

DESCRIPTION

FIG. 1 is a front side while closed view of a keyboard with cover showing my new design;

FIG. 2 is a left side while closed view thereof;

FIG. 3 is a top while closed view thereof;

FIG. 4 is a rear side while closed view thereof;

FIG. 5 is a right side while closed view thereof; and,

FIG. 6 is a top while closed view thereof.

The broken lines in the drawings illustrate portions of the keyboard with cover which form no part of the claimed design.
